UNITED STATES PATENT OFFICE.

GEORGE FARRON, OF DETROIT, MICHIGAN, ASSIGNEE TO KALAMAZOO LOOSE LEAF BINDER CO., OF KALAMAZOO, MICHIGAN.

BINDER DEVICE.

1,194,284.

Specification of Letters Patent. Patented Aug. 3, 1916.

Application filed March 11, 1915. Serial No. 18,826.

To all whom it may concern:

Be it known that I, GEORGE FARRON, a citizen of the United States, residing at Detroit, Michigan, have invented certain new and useful Improvements in Binder Devices, of which the following is a specification.

This invention relates to improvements in binder devices.

The main objects of this invention are: 10 First, to provide an improved binder device which facilitates the use of temporary binders or loose sheet holders, particularly when they are used for record or accounting purposes. Second, to provide an improved binder device which facilitates the handling and manipulation of sheets of temporary binders or loose sheet holders.

Further objects, and objects relating to structural details, will definitely appear from 20 the detailed description to follow.

I accomplish the objects of my invention by the devices and means described in the following specification.

The invention is clearly defined and pointed out in the claims.

A structure which is a preferred embodiment of my invention is clearly illustrated in the accompanying drawing, forming a part of this specification, in which:

30 Fig. I is a plan view of my improved binder device with a temporary binder disposed therein illustrating the manner of use. Fig. II is a vertical longitudinal section on a line corresponding to line 2—2 of Fig. I. Fig. III is a perspective view with the binder and sheets removed. Fig. IV is a vertical longitudinal section corresponding to that of Fig. II, showing a slightly modified form of my invention.

40 In the drawings, similar reference characters refer to similar parts throughout the several views, and the sectional views are taken looking in the direction of the little arrows at the ends of the section lines.

45 Referring to the drawings, I have shown in Figs. I and II an embodiment of my invention particularly designed for the type of binder shown in U. S. Letters Patent No. 878,340, dated Feb. 4, 1908, to Harry F. 50 Bushong, and which comprises a pair of

chambered covers 1 adjustably connected by means of binding strips 2 to clamp or bind the sheets or leaves 3. The adjustment of the binding strip is effected by a screw mechanism 4 in one cover and a ratchet mechanism 5 in the other.

The covers are preferably provided with pivoted clamping or binding members 6 through which the binding strips are disposed. As the details of the mechanism of 60 the binder proper form no part of this invention and as suitable mechanisms are well known I do not describe the same with further detail herein, my invention being designed to facilitate the use of such binders 65 and other binders now in common use.

I mount a pair of holders, designated generally by the numerals 7 and 8, on a pair of supporting base members 9.

The holder 7 comprises a side member 10 and an end member 11, while the holder 8 comprises a side member 12 and an end member 13. These holders are disposed with their end members 11 and 13 in an oppositely inclined relation and with their upper edges meeting. The end members have slots 14 therein adapted to receive the binding strips 2 of a binder arranged in the holders with one cover in each holder and the sheets 3 abutting the end members. The 75 sheets 3 have notches 15 therein adapted to receive the binding strips, the notches being preferably open notches, that is, notches of uniform width, so that the sheets may be conveniently engaged with or disengaged 80 from the binding strips. The sheets shown are provided with index tabs 16.

The end member 11 is disposed at an acute angle to the side member 10 so that the sheets 3 are supported with their upper ends 85 in an inclined relation thereby facilitating the fingering of the sheets.

The end 13 is disposed substantially at right angles to the side member 12 so as to facilitate the alining of the ends of the 90 sheets arranged thereon.

The holder 8 is preferably provided with uprights 17 mounted upon the base to project upwardly at the ends of the side member 12. The side members are preferably 100

supported for adjustment. The adjustment in the structure illustrated is effected by the supporting arms 18 which have longitudinal slots 19 therein engaging the clamping bolts 20.

In use the binder is arranged with one cover in each holder, the sheets in the first instance being all arranged in the holder 7. When entries are to be made the sheets are removed from the holder 7 and after the entries are made the sheets are arranged in the holder 8. It is sometimes a matter of convenience in making up the day's balance sheet, for instance, to distinguish or assort all sheets upon which entries have been made, by offsetting them in the holder 8, as shown in Fig. I. To assist in alining the sheets in their offset or assorted relation the end member 13 in the holder 8 is provided with a guiding rib 21 adapted to engage the notches 15, see Fig. I. The sheets have centrally disposed notches 15' which are adapted to register with the binding strips when the sheets are offset. By thus arranging the sheets they are assorted so that sheets on which entries have been made or which it is desired to otherwise distinguish are all identified.

In the modification shown in Fig. IV I show another form of binder consisting of covers 22 having binding members 23. The removable posts or other leaf engaging members are not shown as post binders are well known in the art. In this modification I provide a removable receiving box 24 which is adapted to be arranged in the holder 8 and may be removed therefrom so that the sheets may be carried to the typewriting machine or carried about for any desired purpose.

My improved binder device greatly facilitates the use of temporary binders in the keeping of records, particularly where it is desired to keep the records on typewriting machines. The sheets are supported so that they are all readily accessible and the wear and tear on the sheets in handling is minimized.

I have illustrated and described my improvements in a simple and practical embodiment. I have not attempted to illustrate the various modifications which might be desirable to adapt my invention to particular binders as I believe the disclosure made will enable such adaptation by those skilled in the art to which this invention relates. I desire, however, to be understood as claiming my improvements specifically in the form illustrated as well as broadly within the scope of the appended claims. In my application, Ser. No. 36,128, filed June 24, 1915, which is a division of this application, I have made claim to certain features originally claimed herein.

Having thus described my invention, what I claim as new and desire to secure by Letters Patent, is:

1. In a support for temporary binders, the combination of a pair of base members, side members disposed in an oppositely inclined relation, end members disposed between said side members to coat therewith, said end members being vertically slotted, the slots being adapted to receive the binding strips of binders arranged with a binder member in each holder, slotted supporting arms for said side members, and clamping screws on said base members engaging said slotted side member supporting arms whereby said side members are supported for adjustment transversely of their coacting end members.

2. In a support for temporary binders, the combination of a pair of holders each comprising a side and an end member disposed with their end members in an oppositely inclined relation and with the upper edges of the end members meeting, said end members having registering slots therein.

3. In a support for temporary binders, the combination of a pair of holders each comprising a side and an end member disposed with their end members adjacent, said end members having openings therein adapted to receive the binding strips of a binder arranged in the support with one binder member in each holder.

4. In a support for temporary binders, the combination of a pair of holders each comprising a side and an end member disposed oppositely with their end members adjacent, said end members having openings therein adapted to receive the binding strips of a binder arranged in the support with one binder member in each holder, said side members being adjustable relative to said end members.

5. In a support for temporary binders, the combination of a pair of holders each comprising side and end members disposed oppositely with their end members adjacent and outwardly inclined, one of said side members being adjustable relative to its end member.

6. In a support for loose sheet binders comprising a pair of separably associated binder members, the combination of a pair of holders each adapted to receive one of said binder members and each comprising side and end members disposed oppositely with their end members adjacent so that binder members may be disposed in said holders and sheets arranged thereon with their inner ends against the holder end members, the end member of one holder being disposed at an acute angle to its side member so that the sheets arranged thereon with their ends abutting the end member are

supported in a stepped relation to facilitate
fingering, the end member of the other
holder being disposed at a right angle to its
side member to facilitate the alining of the
sheets arranged thereon for adjustment of
the binder thereto.

In witness whereof, I have hereunto set

my hand and seal in the presence of two
witnesses.

GEORGE FARRON. [L.S.]
